ATTORNEY

UNITED STATES PATENT OFFICE

SAMUEL J. CAMPBELL, OF GREEN BAY, WISCONSIN, ASSIGNOR TO HUDSON-SHARP MACHINE COMPANY, OF GREEN BAY, WISCONSIN, A CORPORATION OF WISCONSIN

MACHINE FOR FOLDING AND SCALLOPING PAPER SHEETS

Application filed August 19, 1929. Serial No. 386,767.

This invention relates to a machine primarily designed for scalloping the edges of paper napkins and folding the same by continuous operation. The machine is designed to scallop the edges of the paper web as the same is being fed through the machine, and to thereafter sever the web into sections of the required length, and to cross-scallop the sections in the cross-cutting operation, and finally to completely fold the napkins into form for ultimate delivery. The product of the machine, therefore, is a napkin scalloped on all four of its edges and folded to four or more plies in condition for packaging and shipment. The machine, as a whole, is of the general type shown in Patent No. 1,666,086, issued April 17, 1928, and the particular devices constituting the present invention are in the nature of modifications or attachments thereto, so that it is not deemed necessary to describe in full detail all of the features of the machine, as a whole, except in so far as may be necessary to a full and complete understanding of the special features of the present invention.

In the drawings, Figure 1 is a plan view of the machine. Figure 2 is a front view of the machine. And Figure 3 is a sectional elevation taken on line 3—3 of Figure 2.

The machine as shown is of duplicate formation, so that a description of one section or unit thereof will suffice for both.

The machine comprises underframes 10, from each of which springs upwardly a front standard 11 and a rear standard 12. The front standards 11 support a top rail 13 and the rear standards support a similar top rail 14. The front and rear rails 13 and 14 are extended to provide bracket arms 15 which support a paper roll 16 from which the paper web 17 is fed. The rails 13 also afford a support for upwardly extending journal mountings 18 and 19, the former of which terminates in an overhanging head 20 through which is entered an adjusting screw 21 which

affords means for the adjustment of a journal block 22 which mounts a shaft 23. A lower journal block 24 affords a mounting for a lower shaft 25 which carries a roller 26. The shaft 23 affords a mounting for a pair of scalloping rolls 27, each having a scalloping die 28 of sinuous or undulating formation which, in coaction with the roll 26, serve to give a scalloped edging to the paper web 17 and to cut off strips or trimmings 29 from the edges of the paper as it is fed forwardly through the machine. The scalloping rolls 27 are preferably adjustable on the shaft 23, so that the width of the cut may be varied.

After passing through the scalloping mechanism, the paper web proceeds inwardly over an idle roller 30 and thence downwardly over a triangular forming plate 31 which serves to give a longitudinal fold to the advancing web. The folded web is then led downwardly through a pair of forming rolls 32 which are located below the former, and the once folded web is then led between cutting rollers 33 and 34, the former of which is provided with an anvil 35 and the latter of which

is provided with a cross-cutting scalloping die 36, so that as the rolls 33 and 34 rotate they will measure off predetermined lengths of the web and sever the same along an undulating or scalloped line giving the necessary cross-cut to complete the cutting of the napkins.

After passing through the rollers 33 and 34, the advancing web is led between the roller 33 and a folding roller 37, where it is cross-folded by the action of an oscillating folder blade 38 of the character set forth and described in Patent No. 1,666,086. However, the folding and delivery mechanism forms no portion of the present invention and it is therefore not necessary to describe the same in further detail.

One of the shafts 25 is provided at one end with a sprocket 39 which is driven by a sprocket chain 40, and positive rotation is imparted from the shaft 23 by intermeshing spur

gears 41. The roller 34 is driven by intermeshing beveled pinions 42 which derive power from a shaft 43. Suitable gearing 44 is provided for positively driving the rollers 33 and 32, and sprocket mechanism 45 imparts rotation to the other one of the shafts 25 which, through adequate gearing and connections, imparts a driving movement to the sprocket chain 40 which drives the other shaft 25. It is not deemed necessary to describe in detail the method of driving the various mechanisms which are so arranged as to properly time the operation of the scalloping dies 28 and 36, so that the cross-scallops will 10 properly register with the side scallops in giving an accurately cut corner to each of the napkins.

The trimmings 29 fall into a discharge chute 46 which serves to discharge them from 20 the side of the machine.

In operation, the paper web is fed from the roll 16 to the edge scalloping dies which are properly spaced to trim the web to the desired width. The web then passes forwardly 25 and downwardly over the forming blade 31 and through the forming rolls to the cross-cutting rolls which are accurately timed to sever the once folded web by an undulating cross-cut, after which the napkins are finally 30 folded and fed to the point of delivery. The mechanism is one which permits the scalloping operation to be rapidly and accurately formed without complicating or otherwise interfering with the feeding and folding operations, so that the napkins will be fed, cut and 35 folded by the continuous process and delivered with scalloped edges in condition to be packed and shipped.

I claim:

40 1. In a machine of the class described, the combination of a frame adapted to support a paper roll, roller means for producing a scalloped edge cut along each edge of the paper web as it is fed from the roll and means 45 for directing the elimination from the machine of the trimmed off edges, a former plate located beyond the edging means and adapted to longitudinally fold the paper web, cross-cutting roller means located beyond the former plate, one of said rolls being provided with 50 a scallop cutting die adapted to cross-cut the folded paper web along the cutting line, and means for positively driving the edging cutters and the cross cutters in timed relation to 55 one another.

2. In a machine of the class described, the combination of a frame adapted to support a paper roll, roller means for producing a scalloped edge cut along each edge of the paper web as it is fed from the roll and means 60 for directing the elimination from the machine of the trimmed off edges, a former plate located beyond the edging means and adapted to longitudinally fold a paper web, cross-cutting roller means located beyond the 65

former plate, one of said rolls being provided with a scallop cutting die adapted to cross-cut the folded paper web along the cutting line, means for positively driving the edging cutters and the cross cutters in timed relation to one another, and folder mechanism located beyond the cross-cutting rollers and adapted to cross-fold the severed sheets. 70

3. In a machine of the class described, the combination of a frame adapted to support a paper roll, roller means for imparting a scalloped cut to each edge of the paper web as it is fed from the roller and means for directing the elimination from the machine of the trimmed off edges, a triangular former plate located beyond the scalloping roller means and adapted to longitudinally fold a paper web, and a pair of cross-cutting rollers located below the former plate and in transverse relation to the edging roller means, one of the cross-cutting rollers being provided with an undulating die adapted to produce a scalloped cross-cut. 75 80

4. In a machine of the class described, the combination of a frame adapted to support a paper roll, roller means for imparting a scalloped cut to each edge of the paper web as it is fed from the roller and means for directing the elimination from the machine of the trimmed off edges, a triangular former plate located beyond the scalloping roller means and adapted to longitudinally fold a paper web, a pair of cross-cutting rollers located below the former plate and in transverse relation to the edging roller means, one of the cross-cutting rollers being provided with an undulating die adapted to produce a scalloped cross-cut, and an oscillating folding blade located below the cross-cutting rollers and adapted to impart a cross-fold to the severed paper sheet delivered from the cross-cutting rollers. 90 95 100 105

5. In a machine of the class described, the combination of means for supporting a roll of paper, roller means located in alignment with the marginal lines of travel of the paper web for scalloping the edges of the paper web as it is fed from the roll, means for directing the elimination from the machine of the trimmed off edges, means beyond the scalloping roller means for longitudinally folding the scalloped paper web, cross cutting means beyond the folding means and adapted to provide a scalloped cut across the paper web, and means for positively driving the edge scalloping and cross scalloping means. 110 115 120

6. In a machine of the class described, the combination of means for supporting a roll of paper, roller means located in alignment with the marginal line of travel of the paper web for scalloping the edges of the paper web as it is fed from the roll, means for directing the elimination from the machine of the trimmed off edges, means beyond the scal- 125 130

loping roller means for longitudinally folding the scalloped paper web, cross cutting means beyond the folding means and adapted to provide a scalloped cut across the folded paper web, means for positively driving the edge scalloping and cross scalloping means, and cross folding means adapted to receive the once folded paper web from the cross cutting scalloping means and adapted to cross fold the same.

10 In witness that I claim the foregoing I have hereunto subscribed my name this 29th day of July, 1929.

SAMUEL J. CAMPBELL.
